(57) **CLAIM**

An expedition vehicle, as shown and described.

DESCRIPTION

FIG. 1 is a perspective view of an expedition vehicle showing our new design in an open configuration;

FIG. 2 is a front view thereof;

FIG. 3 is a back view thereof;

FIG. 4 is a side view thereof;

FIG. 5 is a top view thereof;

FIG. 6 is a perspective view of the expedition vehicle of FIG. 1 shown in a closed configuration;

FIG. 7 is a front view thereof;

FIG. 8 is a back view thereof;

FIG. 9 is a side view thereof; and,

FIG. 10 is a top view thereof.

In the drawings, the broken line showing of a vehicle depicts environmental subject matter and forms no part of the claim.
